UNITED STATES PATENT OFFICE.

CHARLES A. PSILANDER, OF EASTON, PENNSYLVANIA, ASSIGNOR TO WILLIAM WHARTON JR. & COMPANY, INCORPORATED, OF EASTON, PENNSYLVANIA, A CORPORATION OF PENNSYLVANIA.

TONGUE SWITCH.

Application filed April 18, 1923. Serial No. 632,892.

To all whom it may concern:

Be it known that I, CHARLES A. PSILANDER, a citizen of the United States, residing at Easton, in the county of Northampton and State of Pennsylvania, have invented certain new and useful Improvements in Tongue Switches, of which the following is a specification.

My invention relates to tongue switches and more particularly to means for preventing or obviating lost motion at the heel due to wear of the heel or of the heel socket or of both. In a co-pending application, Ser. No. 621,544, filed Feb. 27, 1923, I propose to accomplish this result through the medium of the switch body an element of which is capable of deflection to vary the diameter of the socket. I now propose to vary this practice by effecting the desired compensatory adjustment solely through an increment in the diameter of the heel of the tongue which is specially constructed for this purpose.

Stated in general terms the present invention resides in a switch tongue having a heel which is adjustable at will to secure a tight fit with relation to its complementary recess or socket. Further stated, the invention embodies any switch tongue whereof the heel has an expandable element designed to accomplish the result stated. It further embodies means for expanding such element at will. It further embodies a simple hold-down for the tongue.

I realize that the invention is susceptible of many specific embodiments and, by way of example, have illustrated a few and will refer to them, more or less in detail, in the course of the following description.

In the annexed drawings,—

Figure 1 is a plan view of the heel end of the improved switch structure; the heel having a wall capable of radial deflection to increase the diameter thereof and established by an open slot; the deflection being accomplished by a wedge movable along the slot.

Fig. 2 is a section on line 2—2 of Fig. 1.

Fig. 3 is a plan view showing a bolt disposed radially of the heel for deflecting the expandable portion thereof.

Fig. 4 is a section on line 4—4 of Fig. 3.

Fig. 5 is a plan view of a structure where-in the heel is expanded through the medium of calking the slot with plastic metal. 55

Fig. 6 is a section on line 6—6 of Fig. 5.

Fig. 7 is a plan view showing a modification of the slot with a vertical wedge or keeper and a co-operating lock.

Fig. 8 is a section on line 8—8 of Fig. 7 60 and showing in detail a simple form of hold-down for the tongue.

The switch body 5, which is or may be constructed as usual, has a flush bottom socket or recess 6 for the heel of the tongue. 65 The switch tongue 7 has its heel 8 formed with an arcuate or segmental slot 9 which has a radial gap or passway 10. There is thus established a floating or expandible wall 11 which may be availed of to increase the diameter of the heel in order to compensate for wear to the end that the heel will have a normal tight fit in the recess or socket 6. 70

Various expedients may be resorted to 75 for expanding the heel. For example, referring to Figs. 1 and 2, the wall 11 may be outwardly sprung or deflected by means of a wedge 12 introduced vertically into the slot 9 and moved along the same to effect the requisite expansion. The wedge 12 has lateral projections 13 which take into an elongated recess 14 in the inner wall of the slot 9 and thus prevent the accidental displacement of the wedge, the recess 14 having entering notches 15 for the projections 13 of the wedge. 80

In Figs. 3 and 4, the adjustment is effected through the medium of a radially disposed bolt 16 and a captive nut 17. The latter bears against the wall 11 and is held from turning by a stop 18; and the bolt impinges against the body of the heel. Evidently by tightening up on the bolt, the head of which is accessible in an inspection box 19, the wall 11 will be outwardly deflected under pressure of the nut. 95

In Figs. 5 and 6 expansion of the heel is provided for by a plug 20 established by calking the slot with plastic metal under 100 exerted pressure, as by hammer blows. Manifestly, the calk or plug can be removed when necessary simply by flowing the metal under the application of heat. If desired,

5 calking may be resorted to in conjunction with the wedges or other means of manual adjustment, but it is quite unnecessary because the open spaces are comparatively small and soon become calked in service by the natural dirt of the street or roadway.

In Figs. 7 and 8, an upstanding bolt 21, the head of which is countersunk in the bottom of the heel so as not to interrupt its flush bearing surface, co-operates with a wedge or shoe 22 slidable on the bolt and countersunk to receive a retaining nut 23.

Figs. 7 and 8 also illustrate a simple form of hold-down which, while associated with the expanding element 22, is not peculiar to that mode of adjustment, but is useful in connection with any of the embodiments. It includes a spring bar 24 which is introduced through opposed slotted portions of the 20 switch body and heel. For example, the inner end of the bar may engage a boss 25 within the hollow portion of the heel. The holding bar bears at 26 against the switch body and beyond that point is formed with an 25 apertured offset arm 27. Above the latter is a forked extension 28 which may be integral with the switch body. A bolt 29 connects the arm with the forked extension and by tightening up on its nut 30 the holding down 30 pressure of the bar can be adjusted from time to time as may be necessary. The accessible parts are preferably housed in an inspection box or casing 31.

Having described my invention, I claim:—

35 1. A switch tongue whereof the heel is capable of bodily adjustment at will to expand or contract the same.

2. A switch tongue having an expansible heel.

40 3. A switch tongue having an expansible heel, and means for expanding it.

4. A switch tongue having an expansible heel, and self-contained means for expanding it.

45 5. A switch tongue whereof the heel has an integral element capable of radial adjustment to vary the diameter of the heel.

6. A switch tongue whereof the heel has an integral element capable of radial adjustment to vary the diameter of the heel, and means for adjusting it.

7. A switch tongue whereof the heel has a radially adjustable wall, and self-contained means for holding it in the adjusted position.

55 8. A switch tongue whereof the heel has an integral radially adjustable wall, and means controllable at will for adjusting it.

9. A switch tongue whereof the heel has 60 an element capable of outward deflection to increase the diameter of the heel to compensate for wear, said element having an integral connection with the body of the heel substantially the depth thereof.

65 10. A switch tongue whereof the heel has

an element springing therefrom and capable of outward deflection to increase the diameter of the heel to compensate for wear.

11. A switch tongue whereof the heel has a spaced element springing therefrom and 70 capable of outward deflection to increase the diameter of the heel.

12. A switch tongue whereof the heel has a spaced element springing therefrom and 75 capable of outward deflection to increase the diameter of the heel, and means for deflecting said element.

13. A switch tongue whereof the heel has an integral radially adjustable wall spaced 80 from the body of the heel, and means operative in the space for adjusting said wall.

14. A switch tongue whereof the heel is slotted to establish a floating wall.

15. A switch tongue whereof the heel has an open slot flanking one of its side walls to 85 provide for increasing the diameter of the heel.

16. A switch tongue whereof the heel has a segmental slot to float one of the walls 90 thereof, and means for deflecting said wall for heel expansion purposes.

17. A switch tongue whereof the heel has a segmental slot to float one of the walls thereof, and self contained means for spacing said wall with relation to the body of 95 the heel.

18. A switch structure, comprising the combination of a body having a tongue bed including a heel socket, and a switch tongue 100 having a heel bodily susceptible of modification at will to initiate or restore normal fit with relation to the socket.

19. A switch structure, comprising the combination of a body having a tongue bed including a heel socket, a switch tongue having an expansible heel adapted to said 105 socket, and means for expanding the heel to compensate for wear.

20. A switch structure, comprising the combination of a body having a tongue bed 110 including a heel socket, a switch tongue co-operating with said body and having a heel provided with a radially adjustable wall, and means co-operating therewith for establishing tight bearing relation of the heel and 115 socket.

21. A switch structure, comprising the combination of a body having a tongue bed including a heel socket, a switch tongue co-operating with said body and having a heel 120 provided with a radially adjustable wall a portion of which is fixed with relation to the heel, and means for adjusting said wall to compensate for relative wear of the heel or 125 socket.

22. A switch structure, comprising the combination of a body having a tongue bed including a heel socket, a switch tongue co-operating with said body and whereof the heel has an element springing therefrom and 130

effective under adjustment to increase the diameter of the heel, and means for adjusting said element.

23. A switch structure, comprising the combination of a body having a tongue bed including a heel socket, a switch tongue cooperating with said body and having its heel slotted to float one of the walls thereof, and means for deflecting said wall to insure normal relative fit of the heel and socket.

24. A switch structure, comprising the combination of a body having a tongue bed including a heel socket, a switch tongue having an expandible heel capable of compensating adjustment, a hold-down member fulcrumed in the switch body to exert downward pressure on the heel, and means for adjusting the leverage thereof.

25. A switch structure, comprising the combination of a body having a tongue bed including a heel socket, and a switch tongue having a heel afforded a flush bearing on the floor of said socket, said heel being radially expandible to establish a continuous side bearing, and means for holding it in the expanded state.

26. A switch structure, comprising the combination of a body having a tongue bed including a heel socket, a switch tongue whereof the heel is hollow and has a continuous bottom bearing and a continuous side bearing, an adjustable spring bar extending into and operating as a hold-down for the heel, a forked extension on the body above the outer end of the bar, and means engaging said extension and bar for regulating the holding down pressure of the bar.

27. A switch structure, comprising the combination of a body having a tongue bed including a heel socket, a switch tongue having a heel afforded a flush bearing in the bot-

tom of the socket and capable of lateral expansion to insure normal fit and wear with relation to the side walls of the socket, and means for holding it in the expanded state. 45

28. A switch structure, comprising the combination of a body having a tongue bed including a heel socket, a switch tongue having a heel afforded a flush bearing in the bottom of the socket and capable of lateral expansion to insure normal fit and wear with relation to the side walls of the socket, and means controllable at will for expanding the heel and for holding it in the expanded state. 50

29. A switch structure, comprising the combination of a body having a tongue bed including a heel socket, a switch tongue having a heel afforded a flush bearing in the bottom of the socket and capable of lateral expansion to insure normal fit and wear with relation to the side walls of the socket, means for holding it in the expanded state, and means effective to prevent rise of the heel. 55

30. A switch structure, comprising the combination of a body having a heel socket of fixed diameter, a switch tongue having a heel of variable diameter, and self-contained means for increasing the diameter of the heel to establish normal fit with relation to the socket. 70

31. A switch structure, comprising the combination of a body having a heel socket of fixed diameter, and a switch tongue whereof the heel has an integer movable with relation thereto to initiate or restore normal fit of the heel with respect to the socket. 75

In testimony whereof I affix my signature.

CHARLES A. PSILANDER.
